[57] CLAIM

I claim the ornamental design for a battery pack casing, as shown.

DESCRIPTION

FIG. 1 is a perspective view showing the front, top, and a first side of the battery pack of the present invention; FIG. 2 is a plan view of the top of the battery pack casing according to the present invention; FIG. 3 is an elevational view of the front of the battery pack casing of the present invention; FIG. 4 is an elevational view of the rear of the battery pack casing of the present invention; FIG. 5 is a perspective view showing the first side of the battery pack casing of the present invention; and FIG. 6 is a plan view of the bottom of the battery pack casing according to the present invention; and, FIG. 7 is an elevational view showing the second side of the battery pack casing according to the present invention. The broken line showing throughout the drawing figures is included for the purpose of illustrating environmental structure only and forms no part of the claimed design.
